The ornamental design for a logo plate, as shown and described.

DESCRIPTION

FIG. 1 is a front perspective view of a logo plate showing my new design.

FIG. 2 is a front elevational view thereof.

FIG. 3 is a back view thereof.

FIG. 4 is a top view thereof.

FIG. 5 is a bottom view thereof.

FIG. 6 is a left side view thereof; and,

FIG. 7 is a right side view thereof.

In the drawings, the irregularly shaped lining for the color gold is only around the two protrusions, and the broken line portions of the figures represent structural elements only and form no part of the claimed design. The "Samsonite Black Label" logo is a registered trademark of Samsonite Corporation.
